UNITED STATES PATENT OFFICE.

FRANK E. HIGGINS, OF GRAND RAPIDS, MICHIGAN.

MOVABLE REFRIGERATOR-CHEST.

SPECIFICATION forming part of Letters Patent No. 241,491, dated May 17, 1881.

Application filed October 8, 1880. (No model.)

To all whom it may concern:

Be it known that I, FRANK ELDREDGE HIGGINS, a citizen of the United States, residing at Grand Rapids, in the county of Kent and State 5 of Michigan, have invented certain new and useful Improvements in Movable Refrigerator-Chests; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 In the drawings, Figure 1 is a transverse vertical section of a movable refrigerator-chest embodying my invention. Fig. 2 is a horizontal section on the line $x\ x$, Fig. 1. Fig. 3 is a similar section on the line $y\ y$, Fig. 1.

20 Like letters refer to like parts wherever they occur.

My invention relates more especially to the construction of that class of movable refrigerator-chests or boxes employed for the transportation of meat, vegetables, and other perishable articles, though certain features set forth will be found equally useful in all classes 25 of refrigerators.

The invention consists, mainly, in the combination, in a refrigerator-chest, of a removable ice box or chamber with a chill-chamber, either fixed or removable, the parts relatively arranged so as to obtain, when the chest is closed, a series of flues for the circulation of 30 the air, and also so as to permit of the separation of the parts for filling, cleaning, airing, &c.; and, secondarily, in details of construction hereinafter more specifically set forth.

The usual manner of packing meats, vegetables, and various perishable articles for transportation in movable refrigerator-chests or boxes is to insert an ice-box within the chest and pack the meat or other article closely around the same. This leads to the condensation 40 of moisture within the storage-chamber and its deposit upon the ice-box, and the meat &c., next the same, so that the meat soon becomes soaked and injured. It also prevents the proper circulation of the air within the chest, and portions of the contents may be frozen, while other portions spoil.

The object of my invention is to obtain and maintain a circulation within the chest whereby the temperature of the chamber will be uniform throughout and its contents preserved; 55 to condense any moisture and conduct it from the chest, whereby the chest and its contents will be kept dry; to render the contents of the chest easily accessible and the chest separable for the purpose of cleaning and repairing 60 the same.

I will now proceed to describe my invention more definitely, so that others may make and use the same.

In the drawings, B indicates an outer box or 65 chest, which may be provided with rollers R R to render it easily movable. Within the box or chest B, and arranged on the bottom thereof, are a series of horizontal strips or cleats, $x\ x$, which support the inner box or chill-chamber, and at the sides and ends are vertical strips $x'\ x''$, which separate the inner box or 70 chill-chamber from the sides of the outer case, B. These strips $x\ x'\ x''$ are usually attached to the box B, and, when the inner box is in 75 place, serve to divide the intermediate space into a series of flues, n , which communicate with the interior of the chill-chamber. In one corner of box B, or at any other suitable point, is a waste-pipe, E, which receives and conducts 80 off the water from the ice-box. The lower end of pipe E should be provided with a trap to prevent the entrance of air or escape of cold air.

C indicates the chill or storage-chamber. It is preferably formed of wood to avoid, as much 85 as possible, the condensation of moisture, and of light material, as well as detachable from box B, so that it can be removed to air and clean the refrigerator, or to renew the same when found necessary. In the lower end of 90 chill-chamber C, in the bottom, and also in the side walls, a , are a number of ports, a' , by which communication is had with flues $n\ n$.

D indicates a removable ice-box, adapted to rest upon and close the top of the chill-chamber C. The bottom I of the ice-box is narrower than the chill-chamber C, and within the ice-box is a vertical partition, S', which, with the outer wall, forms a flue, S, opening below into the top of the chill-chamber, and above 100 into the upper part of the ice-box. Low down on the opposite side of the ice-box is a port or

ports, H, by which the ice-box communicates with flues n.

E' indicates a pipe for conducting the drainage from the ice-box to the waste-pipe E.

5 In order to protect the bottom of the ice-box D, as well as to prevent the condensation of moisture from the chill-chamber on the under surface thereof, a sheet of tarred felt or paper, I', may be employed.

10 A indicates the top for closing the box B and inclosing the ice-box D. It may be provided with hinges, if desired; but in order to be readily detachable is preferably secured by hasps or equivalent devices.

15 For the purpose of filling the chill-chamber C, the top A and ice-box D may be removed, and for the purpose of cleaning or airing the chest, the chill-chamber C may also be removed when the same has been made detachable.

20 When the chill-chamber C has been filled with the article to be transported the ice-box D has been replaced and supplied with ice, and the cover A applied. The cold air from the ice-box will pass through ports H into flues n, thence

25 to the bottom of chill-chamber C, which it enters through ports a', gradually displacing the warm air charged with moisture, and causing the same to rise through flue S and flow over the ice in ice-box D, where the moisture is condensed and escapes through pipe E' and waste-

30 pipe E. This circulation will be maintained as long as any ice remains in the ice-box D.

It is evident that the strips or cleats x x' x²
35 could be attached to the exterior of the de-
tachable chill-chamber C, if preferred.

Having thus described my invention, what I claim, and desire to secure by Letters Patent, is—

1. In a refrigerator-chest for the transportation of perishable articles, a chill or storage 40 chamber surrounded by flues which communicate with the bottom of said chamber, in combination with a removable ice-box adapted to cover the chill-chamber, and provided with a flue which communicates at its lower end with 45 the top of the chill-chamber, and at its upper end with the ice-box, substantially as and for the purpose specified.

2. In a refrigerator, a detachable chill chamber surrounded by circulation-flues, in combination with a detachable ice-box arranged over and adapted to cover the chill-chamber, substantially as and for the purpose specified. 50

3. In a movable refrigerator box or chest, the combination of an outer box or case provided on its interior with cleats or strips arranged with relation to an inner box or case to form flues therewith, a detachable inner box or chill-chamber, a detachable ice-box adapted to cover the chill-chamber, and having a flue connecting therewith, and a waste-pipe for conducting the drainage from the ice-box, substantially as specified. 55 60

In testimony whereof I affix my signature in presence of two witnesses.

FRANK ELDRIDGE HIGGINS.
